RECORD HOLDER

Richard E. Von Meyer, Box 10433, Dallas, Tex.

Filed Oct. 15, 1958, Ser. No. 52,993

Term of patent 14 years

(Cl. D33—3)

FIGURE 2 is a cross sectional view taken on line 2-2 of FIGURE 1 and showing that the cross sectional shape of each of the two end members of the record holder is identical.

I claim:

The ornamental design for a record holder, substantially as shown.
